(57) **CLAIM**

The ornamental design for a nozzle for fluid pump as shown and described.

DESCRIPTION

FIG. 1 is a perspective view of a nozzle for fluid pump showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of portion 8 of FIG. 2, outlined by the dash-dot-dot lines;

FIG. 9 is an enlarged view of portion 9 of FIG. 1, outlined by the dash-dot-dot lines;

FIG. 10 is an enlarged view of portion 10 of FIG. 2, outlined by the dash-dot-dot lines;

FIG. 11 is an enlarged view of portion 11 of FIG. 3, outlined by the dash-dot-dot lines; and,

FIG. 12 is an enlarged view of portion 12 of FIG. 1, outlined by the dash-dot-dot lines.

The broken lines illustrate portions of the nozzle for fluid pump that form no part of the claimed design. The dash-dot-dot lines in FIGS. 1, 2, and 3 outline portions of the nozzle for fluid pump shown enlarged in FIGS. 8-12.
